UNITED STATES PATENT OFFICE.

MARCELLUS B. CLARK, OF AKRON, OHIO.

WATER-BOTTLE.

1,117,327.

Specification of Letters Patent. Patented Nov. 17, 1914.

Application filed April 27, 1914. Serial No. 834,727.

To all whom it may concern:

Be it known that I, MARCELLUS B. CLARK, a citizen of the United States, residing at Akron, in the county of Summit and State 5 of Ohio, have invented new and useful Improvements in Water-Bottles, of which the following is a specification.

This invention relates to improvements in water bottles or bags made of vulcanized 10 rubber, and the object is to provide a bag of molded rubber provided with means whereby the core or mandrel, on which the bottle is formed, may be removed, said bottle provided with what is commercially known 15 as a small or narrow neck connecting the filling funnel with the bag proper.

With the foregoing and other objects in view, the invention consists in the novel construction, combination and arrangement of 20 parts constituting the invention to be hereinafter specifically described and illustrated in the accompanying drawings which form a part hereof wherein is shown the preferred embodiment of the invention, but it is to be 25 understood that changes, variations and modifications can be resorted to which come within the scope of the matter hereinafter claimed.

In the drawings in which similar reference numerals indicate like parts in the different figures, Figure 1, is a perspective view of a bag embodying this invention showing the same during one stage of the manufacture thereof; and, Fig. 2, is a similar view of the complete bag.

Water bottles or bags made on cores are stripped therefrom after their manufacture, and in order to permit the removal of the core, the core must either be made collapsible, the neck of the bottle made sufficiently 40 large to permit the removal of the core, or an opening is made at a point remote from the bottle neck through which the core is withdrawn, the opening being afterward 45 sealed. All bottles manufactured by any of these methods possess certain objectionable features.

The bottle or bag forming the subject matter of this invention is made of vulcanized 50 gum compound and consists of a body portion 1 provided with a supporting strap 2 at the lower end and an integral filling funnel 3 united with the opposite end of the body portion 1 by means of a narrow tubular neck 4. The body portion 1 embodies

a pair of similar side walls intimately united at their edges. The sides are further provided at their upper portions with upwardly-extending ears 5 and 6 similarly fashioned and each formed integral with the 60 filling funnel, and extending from the opening in the filling funnel along the upper edge of one of the shoulders of the bottle is an opening 7 the end of which preferably terminates in a lug 8 integral with the two 65 ears 5 and 6.

In fashioning the bottle it is formed on a core provided with an extended portion fashioned similarly to the ears 5 and 6 and extending between them, whereby they are 70 kept separated until the bottle has been given what is known as a partial or semi-cure. After the first or semi-cure, the core is withdrawn from the interior of the bottle through the opening 7. This operation is 75 easily accomplished by stripping the partially cured bottle from the mandrel or core. After the removal of the core the usual stopper-receiving nipple is inserted in the interior of the neck portion 4 and the opposing faces of the ears 5 and 6 are coated with an adhesive cement or an equivalent 80 for vulcanizing them together, and the bottle subjected to a final cure, which intimately unites the ears 5 and 6 together to 85 close the opening 7. At the same time, the bringing together of the opposing faces of the ears 5 and 6 serves to complete the annular formation of the filling funnel 3 and also serves to hold the stopper-receiving 90 nipple in position. After the final cure, the united ears 5 and 6 are apertured to receive a gromet 9 which serves as a medium for suspending the bag. The intimate uniting of the ears 5 and 6 effectually closes the 95 opening 7 and the ears furnish a hand grasp for the holding of the bag and if it is desired to suspend the same the opening in the gromet 9 provides ready means for this purpose. Besides other functions already 100 described as possessed by the united ears 5 and 6, they serve as a stiffening medium for the upright filling funnel 3 for steadyng the same during the filling operation.

I claim:—

A water-bottle made of a vulcanizable gum compound and comprising a body-portion having two side walls, a filling funnel and a contracted neck, the neck uniting the funnel with said walls, a pair of upwardly- 110

108

extending ears each integral with one of the
walls, with the neck and with the filling
funnel, said neck having a slit or opening
in the upper end at one side thereof between
said ears ultimately closed by intimately
uniting the ears together homogeneously.

In testimony whereof I have hereunto set

my hand in presence of two subscribing wit-
nesses.

MARCELLUS B. CLARK.
